UNITED STATES PATENT OFFICE

2,039,581

DOORBELL SWITCH

David Brown, Chicago, Ill.

Application September 30, 1935, Serial No. 42,778

1 Claim. (Cl. 200—4)

The invention relates to improvements in door bells and has for its primary object the provision of an improved door bell arrangement by means of which one operating push button or the like may be utilized for operating a plurality of door bells or the like.

Other objects will appear hereinafter.

The invention consists in the combinations and arrangements of parts hereinafter described and claimed.

The invention will be best understood by reference to the accompanying drawing forming a part of this specification and in which

Fig. 1 is a face view of a push button mounting adapted for use in an arrangement embodying the invention;

Fig. 2, a section taken substantially on line 2—2 of Fig. 1; and

Fig. 3, a section taken substantially on line 3—3 of Fig. 2 but also including a diametric view of the electric circuits employed in the arrangement.

The embodiment of the invention illustrated in the drawing comprises a plurality of door bells or buzzers 1, 2, 3, 4, 5, 6, 7, 8, 9, 10, 11 and 12, each of which will be located in one of the apartments or rooms of a building. Each of the bells or buzzers 1—12 is connected respectively by a wire, 13, 14, 15, 16, 17, 18, 19, 20, 21, 22, 23 and 24 with a corresponding electric contact 25, 26, 27, 28, 29, 30, 31, 32, 33, 34, 35 and 36 arranged circumferentially on a base block 37 of insulating material. The base block 37 is also provided with a central electric contact 38, which in turn is connected by a wire 39 with one side of a source of current such as a transformer battery or generator. The other side of the source of current is connected by means of a general ground wire 40 and branch wires 41 with each of the electric bells or buzzers 1—12 as shown.

A suitable casing 42, which may be of metal, is arranged as indicated on the base block 37 to enclose the contacts 25—36 and 38, and a push button block 43, which may be preferably of insulating material, is rotatably mounted as indicated centrally on the outer face or top of said casing. The block 43 is also provided with an indicator finger 44 cooperating with a numbered dial on the outer face of the casing 42, as best shown in Fig. 1. A selective electric switch 45 is secured as shown to the inner side of the block 43 in registration with the indicator 44 and carries at its outer end an electric contact 46 adapted and arranged to be shifted selectively into and out of engagement with the various circumferential contacts 25—36 as indicated. The spring switch 45 has its inner end extended to rest against the inner end of a depressible push button 47 mounted in the block 43, and the ex-

treme end thereof is rebent to form a spring electric contact 48 adapted and arranged to make contact with the member 38 when the push button 47 is depressed.

In use one of the electric bells or buzzers 1—12 is located in each room or apartment of a building and the base block 37 with its associated parts is positioned in the usual position of the door bells therefor, said electric bells or buzzers being connected in the electric circuits as indicated in Fig. 3. By this arrangement, when desired the indicator finger 44 may be adjusted to registration with any one of the numbers on the dial on the face of the casing 42, in which position the underlying spring switch 45 will be in registration with the corresponding electric contact 25—36, so that upon depression of the push button 47 the corresponding bell or buzzer will be operated. By adjusting the indicator finger 44 to any one of the other numbers on the dial, the corresponding bell or buzzer may be similarly operated, the single open button arrangement therefore serving to operate selectively the bells or buzzers for each of the rooms or apartments, as will be readily understood.

The specific form and arrangement of parts constitute a simple and effective one for the purpose.

While I have illustrated and described the preferred form of construction for carrying the invention into effect, this is capable of variation and modification without departing from the spirit of the invention. I, therefore, do not wish to be limited to the precise details disclosed, but desire to avail myself of such variations and modifications as fall within the scope of the appended claim.

I claim:

A switch comprising a base member; a plurality of circumferentially arranged electric contacts thereon; a central contact on said base member; a casing on said base member and enclosing said contacts; a push button block rotatably mounted on said casing with its axis of rotation in alignment with said central contact; a push button mounted in said block at the axis of rotation thereof; and a selective spring switch member secured to the under side of and projecting radially from said block, the outer end of said switch member making selective rubbing engagement with said circumferential contacts, the inner portion of said switch member resting against and yieldingly pressing said push button outwardly, and the extreme inner end thereof being rebent to form a spring electric contact arranged to engage said central contact when said push button is depressed.

DAVID BROWN.
